UNITED STATES PATENT OFFICE.

LESLIE E. HOOKER, OF LOWELL, MASSACHUSETTS.

MACHINE FOR HEADING CARTRIDGE-SHELLS.

1,363,597.

Specification of Letters Patent. Patented Dec. 28, 1920.

Application filed April 20, 1918. Serial No. 229,692.

To all whom it may concern:

Be it known that I, LESLIE E. HOOKER, a citizen of the United States, residing at Lowell, in the county of Middlesex and State 5 of Massachusetts, have invented new and useful Improvements in Machines for Heading Cartridge-Shells, of which the following is a specification.

This invention relates to machines for performing one or more operations upon cartridge shells, tubes, or other objects of cylindrical or polygonal outline, which objects are fed through the machines in a continuous row and require to be temporarily 10 stopped and held accurately in predetermined positions.

While certain features of my invention are, or may be, generally applicable to machines for performing other die work, it 15 was devised for, and will be described, in connection with a machine for heading cartridge shells and which performs three operations simultaneously upon three shells. This machine takes the shells in the condition 20 in which they leave an extruding machine, such as the one disclosed in my Patent No. 918,154, issued April 13, 1909, and gives the final shape to the heads.

The extruded tubes have rounded ends, 25 which require to be flattened and provided with the cap pocket, and the shells are also given a finishing draw. Heretofore, these operations have been performed in separate machines, in which the shells are fed horizontally between oppositely reciprocating punches and dies. In the present machine, 30 the three operations are performed simultaneously on three shells, which are fed in a vertical position and in a continuous row between stationary dies and reciprocating 35 plungers. Not only is the work greatly expedited by the use of this machine, but the floor space and power required are much reduced. One of the principal difficulties 40 encountered, which is overcome by the present invention, was to devise means for feeding the shells between the dies and punches and accurately centering them in line with the same. The means by which this is accomplished constitutes one of the main features 45 of the present machine.

The machine, in its existing form will now be described, but it will be understood that, as stated above, the feeding and centering 50 means is not necessarily limited in its use to this particular machine. It will be ap-

plicable wherever cylindrical or polygonal objects are fed to the operating positions in a continuous row, the feeding impulse being imparted to the rearmost shell or object in 60 the row, and where it is necessary to accurately hold the piece being operated upon in a predetermined position.

In the accompanying drawing:—

Figure 1 is a vertical section; and 65

Fig. 2 a plan of the essential parts of the machine embodying my invention;

Fig. 3 is a detail section on line 3—3 of Fig. 2;

Fig. 4 is a sectional view of a shell as it is 70 fed to this machine;

Figs. 5 and 6 are similar views showing the results of the first two operations;

Fig. 7 is an elevation of a shell as it appears when it leaves the machine after the 75 third operation, and

Fig. 8 is an end view of the finished head of the shell.

As actually built and as shown in the plan view, two rows of the extruded tubes 20 are 80 simultaneously fed, there being two sets of dies and plungers, so that six shells are operated upon at each descent of the crosshead. It will be understood that the machine in its main features is an ordinary die-shaping 85 press, the vertically reciprocating crosshead of which carries the punch carrying plate 1, while the dies are mounted in the stationary die plate or anvil 2. Plate 1 carries the punches 3, 4 and 5, and plate 2 the dies 6, 7 90 and 8. Suspended beneath the die plate by rods 9 is an ejector head 10. On a level with the top of the die plate 2 is a raceway 11 through which the shells 20 are fed to the dies by means of a pusher 12, reciprocated 95 by a cam 13 and spring 14, the shells being supplied in front of said pusher by any suitable feeding means. As stated, in the actual machine, there are two sets of punches and dies and two raceways and pushers but as 100 they are duplicates, it will be sufficient to describe one set only.

Punch 3 and die 6 perform the first operation of flattening the head and partially forming the cap pocket 21; see Fig. 5. 105 Punch 4 and die 7 perform the second operation of finishing the cap pocket 22, see Figs. 6 and 7, and stamping letters or marks on the head, see Fig. 8. Finally, punch 5 forces the shell through the drawing die 8, which 110 slightly reduces it in diameter and elongates it. The shells have of course to be ejected

or raised out of dies 6 and 7, in order to move onward in the raceway, and this is done by the ejector head 10, which is provided on top with a knockout plate 15, supported on springs 16. Said plate encounters, shortly before arriving at the top of its stroke, the plugs 17, on which rest pins 18, 18, the upper ends of which bear against the movable members 19 of said dies.

10 Another feature of the present invention, and one which is applicable to any cartridge shell heading machine, consists in the construction of the heading dies, each of which comprises the member 19. In the first die, 15 said member, which is known as a bunter, is a solid flanged block, provided on its active face with a central projection 31, which forms the depression 21, or the rudimentary pocket for the primer. In the second die, 20 the member 19 is bored through for the reception of the bunter pin 32, which completes the primer pocket 22, while the annular face of this member 19 stamps the lettering on the head of the shell. Both members 19 are 25 slideable in their die blocks to eject the shells.

Heretofore in shell heading machines, both the heading dies have been integral structures, and the primer pocket was made of full depth at the first operation. Difficulty was encountered in accurately centering the bunter pin of the second die so that it would exactly enter the pocket, which its function was to complete. The integral die and bunter pin were made in a hydraulic 30 press, which also formed the lettering on the die. In the operation of hardening the pin sometimes got out of true and it was not practicable to subsequently grind it true without defacing the lettering. The consequence was that the pins often broke off at their juncture with the dies. By making the pin of the second die a separate piece, it can be accurately centered and trued and, as the first bunter merely makes a slight depression in the head of the shell, the edge of which is chamfered or beveled, the danger of breaking off the pin is entirely obviated.

To accurately locate and hold the shells in position for the punches to force them into the dies, I mount on the die plate two vertical plates 25, the space between which forms a continuation of the raceway 11. Each plate 25 is provided with two rows of sockets 26, see Fig. 3, bored in from the rear side so as to leave a constricted mouth 27 in the front side. A ball 28 is placed in each socket with a spring 29 behind it and then plates 30 are bolted on the backs of the plates to close the sockets. The balls are held normally, by 50 the springs, partially projecting from the mouths of the sockets and are caused to recede when the line of shells is fed forward by the pusher 12. The sockets in each row are separated by a distance substantially 55 equal to the diameter of the shells, and are so

located that one of the row of shells is always held exactly in line with each die. At each forward impulse of the pusher, each shell snaps over the nearest balls and comes to rest in the adjacent space. It will be seen that 70 this device provides a very simple, practically indestructible and yet extremely accurate spacing and centering means for the shells.

The operation has been sufficiently described in the course of the above description, it is believed. In the upward movement of the crosshead, the shells in dies 6 and 7 are lifted by plate 15 with a quick yielding blow into line with the row of shells and then the 80 pusher moves the row forwardly, bringing other shells into line with the dies. In its downward stroke, three shells (or six in the actual machine) are operated upon as described, those in dies 8 being driven through 85 and falling into a suitable receptacle.

What I claim is:—

1. In a machine for heading cartridge-shells or the like, the combination with a plurality of aligned dies and coöperating punches, of a guideway for the shells adjacent to said dies, means to feed a column of shells intermittently along said guideway, and spring-pressed means in the sides of the same to center the shells successively in said dies.

2. In a machine for heading cartridge-shells or the like, the combination with a plurality of aligned dies and coöperating punches, of a guideway for the shells adjacent to said dies, means to feed a column of shells intermittently along said guideway, spring-pressed means in the sides of the same to center the shells successively in said dies, and means to return the shells into 105 said guideway from said dies.

3. In a machine for heading cartridge-shells or the like, the combination with a plurality of aligned dies and coöperating punches, of a guideway for the shells adjacent to said dies, the inner sides of said guideway having aligned sockets with restricted mouths, balls in said sockets, springs to normally maintain said balls partially projecting from the mouths of said sockets, the 115 sockets being so spaced longitudinally of the guideway as to accurately center the shells successively in said dies, and means to return the shells into the guideway from each die except the last.

4. In a machine for heading cartridge-shells or the like, the combination of a die for forming a rudimentary cap pocket in the head of a shell, a die for finishing said pocket and the face of the head, and a die for giving 125 a finishing draw to the shell, said dies being arranged in line, a reciprocatory carrier and punches coöperating with said dies carried thereby, means to intermittently feed a row of shells in front of said dies, and spring- 130

pressed means to hold a shell in alinement with each of said dies while the punches are operating on the same.

5. In a press for acting on objects in dies, the combination with the latter, of a guideway to conduct the objects into alinement with the dies, and means to intermittently feed a row of the objects through said guideway, the inner faces of said guideway being provided with two rows of alined sockets, those in each row being spaced apart a distance substantially equal to the diameter of the objects and the mouths of said sockets being slightly contracted, a ball in each 10 socket of slightly greater diameter than the mouth of the same, and a spring in each socket behind said ball.

6. In a machine for shaping the heads of cartridge-shells or the like, the combination with a plurality of alined dies and their co-operating punches, of means to feed shells in a row to said dies, yielding means to automatically center the shells in front of the latter while the punches are operating, 25 and means to eject the shells from the dies to permit them to be fed to the next succeeding die.

7. In a machine of the class described, the combination of a guideway for the work pieces, comprising parallel walls having two rows of equally spaced sockets opening in the inner faces of said walls, spring-pressed spacers in said sockets, and means to feed a row of work pieces intermittently through 30 said guideway, whereby said pieces are temporarily held accurately in predetermined positions.

8. A feeding mechanism for presses, comprising a guideway having parallel walls to receive a row of work pieces, means to move 40 said row forwardly step by step, and a row

of spring-pressed catches projecting from the inner faces of said walls, said catches being so spaced as to accurately position each work piece successively.

45

9. In a machine for finishing the heads of cartridge-shells made from extruded tubes, the combination with two dies for acting on the heads and one drawing die, of coöperating reciprocating punches, a raceway in 50 which the tubes are placed in a row, a reciprocatory pusher in the rear end of said raceway, spring-pressed spacers projecting into that part of said raceway over said dies, movable headers in said heading dies, 55 ejector pins beneath said headers, and means connected to the punches for actuating said ejectors near the end of the upstroke of said punches.

10. The combination of a plurality of 60 alined dies and coöperating punches, a guideway for the work pieces, above said dies, means to feed a row of work pieces through said guideway intermittently, spring-pressed balls projecting into said 65 guideway so located as to hold each piece successively over each die, and means to return the work pieces from said dies into said guideway.

11. The combination with a die and 70 plunger, of means to feed objects successively between and into line with the same and hold them during the operation, comprising a raceway in which a row of the objects are placed, means to move said row 75 step by step, and spring-pressed catches in the sides of said raceway, spaced to engage between each adjacent pair of objects.

In testimony whereof I have hereunto set my hand.

LESLIE E. HOOKER.
